UNITED STATES PATENT OFFICE.

PETER BEST, OF ELIZABETH, NEW JERSEY.

CAR-FENDER.

SPECIFICATION forming part of Letters Patent No. 561,155, dated June 2, 1896.

Application filed July 15, 1895. Serial No. 555,957. (No model.)

To all whom it may concern:

Be it known that I, PETER BEST, a citizen of the United States, and a resident of (North) Elizabeth, in the county of Union and State of New Jersey, have invented certain new and useful Improvements in Car Fenders or Guards, of which the following is a specification, reference being had to the accompanying drawings, forming a part thereof, in which similar letters of reference indicate corresponding parts.

This invention relates to car fenders or guards; and the object thereof is to produce a device of this character which is simple in construction and operation and which will prevent the serious and frequently fatal results which often occur when a person or other object is struck by a car while in motion; and with this and other objects in view the invention consists in the construction, combination, and arrangement of parts hereinafter described and claimed.

The invention is fully disclosed in the following specification, of which the accompanying drawings form a part, in which—

Figure 1 is a side elevation of the end of a car provided with my improved fender or guard in a position ready for use; Fig. 2, a similar view showing the position which the parts assume when a person is struck, and Fig. 3 a bottom plan view.

In the practice of my invention I secure beneath the platform A of a car hangers B, to which is pivotally secured a fender consisting of a frame composed of side bars C, which are united by transverse rods D and d, the first of which is located near the middle of the side bars C and the last of which near the front end thereof, as shown in Fig. 3, and between these rods there is a body portion of wire-mesh or similar material.

Rigidly connected with the front end of the car, near the top of the dashboard and with the front end of the platform, is a second or vertical fender-frame E, consisting of side bars, to the lower end of which is secured, by hinges or otherwise, a short supplemental frame e, which extends outwardly and downwardly, and to the outer or forward end of which is hinged an auxiliary frame e', which is provided at its front end with rollers e'', and hinged to the top of the second or vertical

fender-frame E is a third or outer fender-frame F, which consists of two sections, the lower section f of which is hinged to the section F below the middle thereof, and said lower section is also hinged at its lower end to the auxiliary frame e'', as shown at f', and hinged to the lower end of the section f is a supplemental frame f'', having a yielding bar f''', of rubber or similar material. The section f is provided with a body portion of wire-mesh or similar material, and the fender-frame F is provided with a plurality of flat metal springs G, which are connected with the top thereof, as shown as g, and bent outwardly and downwardly and secured to the lower end of said frame, as shown at g', thus forming a body portion of springs for the outer fender-frame F.

The auxiliary fender or guard f'', hinged to the section f of the fender-frame F, is provided with a top plate H, which is hinged to side plates h, connected with the section f, as shown as h'.

Extending vertically through the platform is a rod K, to the bottom of which is secured an arm k, the end of which is provided with a series of perforations or holes k', and pivotally connected with the lower end of the outer fender-frame F and centrally of the under side thereof is a rod L, the free end of which is provided with a downwardly-extending projection l, adapted to be inserted through one of the perforations k', as shown in Figs. 1 and 3. The shoulders l', by means of which the rod L is pivotally connected with the fender-frame F, extend downwardly and overlap the junction of the said frame F and the section f, as shown in Figs. 1 and 2.

Connected with the fender-frame C, by means of a transverse rod M, is a bar m, which extends upwardly and is pivotally connected at m' with the outer fender-frame F, and also pivotally connected with each side of the frame E are arms n, the outer ends of which are each provided with a downwardly-projecting head N, adapted to operate in connection with lugs or pins n', secured to or formed on the sides of the frame F, and pivotally connected with a rod which extends through the arms n is a vertical rod O, which extends upward through an eye or loop o, connected with the top of the dashboard.

The hinged connection between the frame

F and the section f thereof is so formed that when these parts are in the position shown in Fig. 1 they will not be exactly in a straight line; but it will be slightly outwardly convexed or inclined, the object of which is to prevent the accidental displacement thereof from the operative position.

The operation will be readily understood from the foregoing description when taken in connection with the accompanying drawings. When the car is in motion, the parts of my improved fender or guard will be in the position shown in Fig. 1, with the outer fender-frame extended, and the supplemental frame e' of the vertical frame E will be extended adjacent to the track. If a person or object should be struck by the car when in motion, said person or object will be thrown against the outer frame F and its hinged section f, and these parts will at once be thrown in the position shown in full and dotted lines in Fig. 2, and the fender-frame C will be borne down to and in contact with the track, as also shown in Fig. 2, by the arm or bar m, and in this position the pivoted arms n will connect with the projection n', as shown in Fig. 2, and hold the frame F in the position shown in said figure. Ordinarily the person or object struck will be received upon or supported by the fender in the position shown in dotted lines in Fig. 2; but if by any possibility such person or object should pass under the hinged section f and e' said person or object will be received upon or caught by the fender C, which is in the depressed position shown in Fig. 2. It will be observed that the pivoted arms n may be operated by the rod O when it is desired to release them from the projections n', and the vertical rod K, which extends through the platform of the car, may be operated to draw back the pivoted rod L and secure or hold the outer fender-frame F in the depressed position shown in Fig. 2 until it is desired to release the same and again restore it to the operative position shown in Fig. 1, which may also be done by means of the rod K. It will thus be seen that I accomplish the object of my invention by means of a device which is simple in construction and operation, and which can readily be attached to any car without change in the construction thereof, and which is comparatively inexpensive.

Having fully described my invention, I claim and desire to secure by Letters Patent—

1. The combination with a car, of a fender-frame pivotally supported beneath the platform thereof, a vertical frame secured to the end of the car and provided with a projection, to which is hinged a supplemental frame, adapted to be supported adjacent to the track, an outer frame composed of hinged sections the upper end of which is hinged to the vertical frame and the lower end of which is hinged to the outer end of the supplemental frame, the upper section of the outer frame being pivotally connected with the frame beneath the platform by means of a rod, and a vertical rod extending through the platform of the car and having an arm secured to the lower end thereof and a rod pivotally connected with the outer frame at the hinged connection of the separate parts thereof, and the inner end of said rod being adapted to be connected with said arm, substantially as shown and described.

frame beneath the platform by means of a rod, and a vertical rod extending through the platform of the car and having an arm secured to the lower end thereof, and a rod pivotally connected with the outer frame at the hinged connection of the separate parts thereof, and the inner end of said rod being adapted to be connected with said arm, substantially as shown and described.

2. The combination with a car, of a fender-frame pivotally supported beneath the platform thereof, a vertical frame secured to the end of the car and provided with a projection, to which is hinged a supplemental frame, adapted to be supported adjacent to the track, an outer frame composed of hinged sections the upper end of which is hinged to the vertical frame and the lower end of which is hinged to the outer end of the supplemental frame, the upper section of the outer frame being pivotally connected with the frame beneath the platform by means of a rod, and a vertical rod extending through the platform of the car and having an arm secured to the lower end thereof and a rod pivotally connected with the outer frame at the hinged connection of the separate parts thereof, and the inner end of said rod being adapted to be connected with said arm, substantially as shown and described.

3. The combination with a car, of a fender-frame pivotally supported beneath the platform thereof, a vertical frame secured to the end of the car and provided with a projection, to which is hinged a supplemental frame, adapted to be supported adjacent to the track, an outer frame composed of hinged sections the upper end of which is hinged to the vertical frame and the lower end of which is hinged to the outer end of the supplemental frame, the upper section of the outer frame being pivotally connected with the frame beneath the platform by means of a rod, and a vertical rod extending through the platform of the car and having an arm secured to the lower end thereof and a rod pivotally connected with the outer frame at the hinged connection of the separate parts thereof, and the inner end of said rod being adapted to be connected with said arm, and an auxiliary frame connected with the lower end of the lower section of the outer frame and adapted to be supported adjacent to the track, substantially as shown and described.

In testimony that I claim the foregoing as my invention I have signed my name, in presence of two witnesses, this 12th day of July, 1895.

PETER BEST.
